UNITED STATES PATENT OFFICE.

WILLIAM REICHLE, OF SPRINGFIELD, ILLINOIS.

CARPET-STRETCHER.

SPECIFICATION forming part of Letters Patent No. 758,562, dated April 26, 1904.

Application filed June 3, 1903. Serial No. 159,854. (No model.)

To all whom it may concern:

Be it known that I, WILLIAM REICHLE, a citizen of the United States, residing at Springfield, in the county of Sangamon and State of Illinois, have invented certain new and useful

Improvements in Carpet-Stretchers, of which the following is such a full, clear, and exact description as will enable others skilled in the art to which it appertains to make and use my

said invention.

My invention relates to carpet-stretchers of that class which employs extensible frames in connection with stretching devices for stretching the carpet.

The purpose of my invention is to provide a carpet-stretcher formed of two sections suitably connected so that the sections may be folded on each other and each section having an extensible frame, the whole being so constructed and arranged that the stretcher may take a double hitch on the carpet at each setting of the stretcher, as hereinafter more fully explained; to provide means for securing the extensions in their extended position, and to provide means for simultaneously moving both of the stretcher-bars, one traveling twice as far as the other.

With these ends in view my invention consists in the novel features of construction and combinations of parts shown in the annexed drawings, to which reference is hereby made, and hereinafter particularly described, and finally recited in the claims.

Referring to the drawings, Figure 1 is a top plan of the complete apparatus. Fig. 2 is an enlarged vertical transverse section on the line 2 2 of Fig. 1. Fig. 3 is an enlarged vertical transverse section on the line 3 3 of Fig. 1, and Fig. 4 is an enlarged detached perspective view of one of the clamps.

Similar reference-letters designate like parts in all of the views.

The main front frame is rectangular in form and has channeled side bars A, joined by a cross-piece A'. A rectangular extension-frame A² slides in the channels in the side pieces A and has in its edges notches a, in which fit cam-shaped clamps a', which are mounted on the said pieces A and serve to clamp the side pieces of the extension-frame against the

side pieces of the main frame, the position of the extension relative to the main frame being determined by the notches in which the clamping devices engage. The form of the clamping device is clearly shown in Fig. 4. 55

The main rear frame consists of channeled side pieces B, joined by cross-pieces B'. The rear frame is connected with the front frame by hinges b. Notched extension-bars B² are separately slideable in the channels of the bars B. The extension-bars B² are separately adjustable in order that they may be made to fit against a slanting base-board or a slanting wall. Clamping devices b' engage in the notches in the extension-bars to secure the extension- 65 bars in position.

Guide-bars A³ and B³ are secured to the bars A² and B, respectively. Draw-bars A⁴ and B⁴ slide on and are guided by the guide-bars A³ and B³, respectively. The draw-bars 70 have downwardly and forwardly projecting teeth on their under side which engage in the carpet during the operation of stretching. A spring B⁵ connects the bar B⁴ with the rear cross-piece B'. In the front section of the main frame the extension-frame slides between the slide-bars A. In the rear section the extension-bars slide on the outside of the bars B. 75

A horizontal winch D turns in standards a² 80 on the frame A² and has on each side an elongated hub or shaft extending outward beyond the standards. A ratchet d on one hub of the winch is engaged by a pawl d' on one of the standards a² to prevent backward turning of 85 the winch. The drum of the winch has transverse holes, in which a rod may be inserted to turn the winch. A sheave d² is connected with the rear cross-piece of the extension-frame A². Cords E have one end connected with the draw-bar B and the other end connected with the hubs of the winch, so that when the winch is turned rearward the cords will wind on the hubs of the winch. Cords F pass through the draw-bar A⁴ and have one end connected with the winch, so that when the winch is turned rearwardly the cords will wind on the drum. These cords are knotted near where they pass through the draw-bar, so that whichever way the cords are moved they will pull on the 90

95

100

draw-bar. The rear ends of the cords F are connected with a cord F', which passes around the sheave d² and is connected with the drum of the winch, so that when the winch is turned 5 rearwardly the cord will unwind from the drum. The diameter of the drum of the winch is just twice the diameter of the hub on the winch.

It will be seen that the bar A⁴ being connected with the drum and the draw-bar B⁴ being connected with the hubs of the winch the draw-bar A⁴ will travel just twice the distance that the bar B⁴ travels for each revolution of the winch. During the operation of stretching the draw-bar A⁴, traveling twice the distance of the bar B⁴, will not only take up the slack produced by the bar B⁴, pushing the carpet forward, but will also stretch the carpet between the winch and the bar B⁴ to the 15 same extent that the bar B⁴ has stretched the carpet in its rear.

The two sections of the stretcher are substantially equal in length, and the stretcher as a whole is preferably of such length that 25 one setting of the stretcher will suffice to stretch the carpet across a room of ordinary width—say fifteen feet; but the stretcher may be made of any other suitable or convenient size without departing from my invention, the 30 sections folding on each other for convenience in transportation or storage.

The spring B⁵ serves to retract the draw-bars A⁴ and B⁴ after the stretching has been completed and restore them to the position to 35 begin the next stretching.

The operation of the stretcher is as follows: The extension-bars B² are extended until the distance between the draw-bar B⁴ and the rear end of the extension-bars B² is substantially 40 one-half of the length of the carpet to be stretched. The front extension-frame is then moved forward and clamped in such position that the extended lengths of the sections of the frame will be approximately equal. The 45 teeth of the draw-bars A⁴ and B⁴ are then engaged in the carpet and the winch is turned rearward to cause the cords to wind on the winch and pull the draw-bars forward so as to stretch the carpet, as already described.

Upon raising the front end of the stretcher 50 so as to withdraw the teeth of the draw-bars from the carpet the spring B⁵ will react and retract the draw-bars into position for the next stretching.

I am aware that carpet-stretchers having 55 extensible frames have heretofore been used. I therefore do not claim that feature broadly.

Having fully described my invention, what 60 I claim as new, and desire to secure by Letters Patent, is—

1. In a carpet-stretcher, the combination of a main frame, a winch mounted on said frame and having a drum and hubs, the diameter of said drum being twice the diameter of said hubs, draw-bars slidable on said frame and connecting devices connecting said draw-bars with said winch in such manner that one of said draw-bars will travel twice the distance that the other travels for each revolution of the winch, as set forth. 65

2. In a carpet-stretcher, the combination of a main frame, a winch mounted on said frame and having a drum and hubs, the diameter of said drum being twice the diameter of said hubs, draw-bars slidable on said frame, connecting devices connecting said draw-bar with said winch and means for simultaneously retracting said draw-bars, as set forth. 75

3. In a carpet-stretcher, the combination of a main frame consisting of sections having a 80 hinge connection, an extension-frame slidable on one section of the main frame, separately-adjustable extension-bars slidable on the other section of said frame, means for clamping said extension-frame and extension-bars, a winch 85 mounted on said extension-frame, draw-bars slidable on the main frame, connecting devices connecting said draw-bars with said winch, and means for retracting said draw-bars, as set forth. 90

In witness whereof I have hereunto subscribed my name, at Springfield, Illinois, this 29th day of April, 1903.

WILLIAM REICHLE.
